(57) **CLAIM**

The ornamental design for a wireless input device, as shown and described.

DESCRIPTION

FIG. 1 is a perspective view of our wireless input device showing our new design included therein;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines represent portions of the structure that form no part of the claim.
